UNITED STATES PATENT OFFICE.

MICHAL ZARADZKI, OF CARNEGIE, PENNSYLVANIA.

ELEVATOR SAFETY DEVICE.

1,165,929.

Specification of Letters Patent. Patented Dec. 28, 1915.

Application filed July 12, 1915. Serial No. 39,841.

To all whom it may concern:

Be it known that I, MICHAL ZARADZKI, subject of the Czar of Russia, residing at Carnegie, in the county of Allegheny and State of Pennsylvania, have invented certain new and useful Improvements in Elevator Safety Devices, of which the following is a specification.

This invention relates to certain new and useful improvements in elevator safety devices.

The primary object of this invention is to provide an attachment for elevators manually operable from the elevator car whereby the car may be caught and safely held suspended within the shaft in the event of an accidental severing of the hoisting members or a releasing of the hoisting mechanism.

20 A further object of the device is the prevention of accidents to passengers and goods which are sometimes caused by the sudden descent of an elevator car caused by some accident to the elevator mechanism.

25 A still further object is to provide normally retracted supporting bolts for an elevator car operable by the power mechanism of the elevator and controlled by the operator of the car by means of a vertically arranged pull cord extending through the car.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like designating characters refer to corresponding parts throughout the several views, Figure 1 is a side elevation of an elevator shaft and car provided with the present device and partially broken away. Fig. 2 is a similar elevational view of an adjacent side of the car. Fig. 3 is a top plan view thereof. Fig. 4 is a central longitudinal sectional detail view through the clutch mechanism of the device, and Fig. 5 is a perspective view of one of the supporting bolts detached.

Referring more in detail to the drawings, the usual vertical shafting 10 is provided within the four corners of the elevator shaft and having a rectangular top frame 11 mounted thereon, while a car 12 is slidably

positioned within the shaft adapted for raising and lowering under the control of the operator.

Power means for elevating the car 12 is provided in the form of a driven shaft 13 carried by the frame 11 which may be operated by any form of motor desired and which motor is not herein illustrated, the said shaft 13 having a gear 14 at one end, while a second shaft 15 journaled parallel to the shaft 13 upon the said top frame 11 has a gear 16 operatively connected to the afore-mentioned gear 14 by means of an idler gear 17 intermediately positioned with respect to the gears 14 and 16 mounted upon the said top frame by means of a stub shaft 18. Similar drums 19 are carried upon the said shafts 13 and 15, having hoisting cables 20 secured thereto and wrapped therearound and extending over sheaves 21 mounted upon the frame 11 and secured as at 22 to the top of the car 12. It will be understood that by revolving the shaft 13, the shaft 15 is revolved in the same direction and the drums 19 are thus turned for winding the cables 20 thereon for raising the car 12 and for unwinding the said cables therefrom during the lowering operation of the car.

Supporting bolts 23 are positioned through horizontal side openings 24 in the opposite beams 30 carried by the shaft timbers 10 and are arranged in opposite pairs at desired intervals throughout the height of the elevator shaft, the said bolts being normally retained in their retracted inclined positions by means of their outwardly positioned weighted ends 25 and in which position the said bolts engage the inclined upper faces 26 of the said slots 24.

An operating cord 27 is secured as at 28 to the outer ends of each of the bolts 23, the said cords running over pulleys 29 carried by the supporting beams 30 and thence over pulleys 31 carried by upright brackets 32 upon the said beams 30 from whence a single strand 33 is carried over a pulley 34 upon the beams 10 and thence over a pulley 35 upon a cross bar 36 of the shaft frame.

The arrangement of bolts and operating cords and strands is identical at opposite sides of the elevator shaft, and the said strands 33 from each of the opposite pairs of bolts are connected together as at 37 and united to a single strand 38 which passes upwardly at the side of the shaft and extends over a pulley 39 upon the top frame

10 and thence to a winding drum 40 to which the free end thereof is secured. The said drum 40 is secured to a sleeve 41 longitudinally slidable upon a shaft 42 by means of 5 a spline 43, the said shaft 42 being journaled upon the said top frame 11 intermediate the afore-mentioned shafts 13 and 15. A gear 44 is carried by a sleeve 45 which is journaled in a casting 46 carried by the frame 11 10 while the said gear 44 is in constant mesh with a similar gear 47 carried by the driven shaft 13. The afore-mentioned shaft 32 which is carried by the said frame 11 is journaled at one end within the sleeve 45. 15 The sleeve 41 is provided with clutching lugs 48 upon the end thereof adjacent the said gear 44, which gear is provided with complementally formed clutching teeth 49. It will thus be evident that the usual turning 20 of the shaft 13 during the operation of the elevator results in freely turning the gear 44, while the shaft 42 remains stationary, but, upon an interengagement of the clutch teeth 48 and 49, such a turning of the gear 25 44 necessarily results in revolving the sleeve 41 and its drum 40.

An operating rocker lever 50 is pivoted to any convenient support 51 above the frame 11 and engages a clutch sleeve 52 upon 30 the sleeve 41, while a pull cord 53 is secured to the free end of the lever 50 and extends through an opening 54 in the roof of the car 12 and then passes vertically completely through the car and is secured at a convenient point 55 at the bottom of the elevator shaft.

When the car 12 is being normally operated the clutch members 48 and 49 are out of engagement and the bolts 23 are outwardly inclinedly positioned. In the event 40 of an accident such as the severing of the hoisting cables 20 resulting in a sudden descent of the car, the operator thereof grasps the cord 53 and by exerting a pull thereon 45 shifts the clutch sleeve 41 which engages the clutch members 48 and 49 whereby the shaft 42 and its drum 40 are revolved with the revolving gear 44 which is constantly operated by the motor, not shown. This turning 50 of the drum 40 winds the rope 38 thereon and exerts an upward pull upon the cords 33 and forces the opposite pairs of bolts 23 wherever arranged in the shaft, through the beam openings 24 and the car 12 is caught 55 by the adjacently positioned bolts arranged

therebeneath, the car being cushioned in its seating thereon by means of springs 56 carried by the bottom of the car, this suspended position of the elements being best illustrated in dotted lines by Fig. 1 of the drawing. It will be seen that the operator of the car may readily position the bolts 23 inwardly whenever desired and thus catch the car during any sudden descent thereof occasioned by a severing of the hoisting cables 60 during their operative moving of the car 12, and whereby the car will be prevented from dropping to the bottom of the elevator shaft.

While the form of the invention herein shown and described is what is believed to 70 be the preferred embodiment thereof, it is nevertheless to be understood that minor changes may be made without departing from the spirit and scope of the invention as claimed.

What I claim as new is:—

1. A device of the class described, comprising in combination with an elevator car and the shaft frame thereof, operating shafts for the said car, normally retracted bolts carried by the shafting and supportingly projectable inwardly thereof within the path of travel of the said car, retracting means for the said bolts, cushioning springs upon the bottom of the said car at the sides 80 thereof adjacent the said bolts, and manually adjustable connections between the said bolts and operating shafts.

2. A device of the class described, comprising in combination with an elevator car 90 and the shaft frame thereof, operating shafts for the said car, normally retracted bolts carried by the shafting and supportingly projectable inwardly thereof within the path of travel of the said car, retracting means for the said bolts, cushioning springs upon the bottom of the said car at the sides 95 thereof adjacent the said bolts, an operating drum for the said bolts connecting cords between the said bolts and operating 100 drum, clutch control connections between the said drum and operating shafts, a clutch operating member for the said last-named means, and a cord connected between the said clutch operating member and the bottom 105 of the shaft and freely extending through the said car.

In testimony whereof I affix my signature.

MICHAL ZARADZKI.
